UNITED STATES PATENT OFFICE.

JOHN G. BARTELL, OF ST. PAUL, MINNESOTA.

SWINGING SCAFFOLD.

1,188,238.

Specification of Letters Patent. Patented June 20, 1916.

Application filed January 3, 1916. Serial No. 69,860.

To all whom it may concern:

Be it known that I, JOHN G. BARTELL, a citizen of the United States, residing at St. Paul, in the county of Ramsey and State of Minnesota, have invented a certain new and useful Improvement in Swinging Scaffolds, of which the following is a specification.

This invention pertains to hanging scaffolds, such as are employed in the erection of modern buildings, and in cleaning, painting, and repair work.

The objects of the invention are to produce a scaffold the deck or platform of which shall be clear and free from obstructions of any kind; which being made up of unit sections may be lengthened to any desired extent; which may be raised or lowered at will, and if need be, by a single workman; and which may be permitted to descend by gravity and at regulated speed, when desired.

To these ends the invention comprises various features, details, and combinations of parts hereinafter described and claimed.

The accompanying drawings illustrate a preferred embodiment of the invention.

In these drawings: Figure 1 is a front view of the suspended scaffold, two complete units or sections and the end of a third being shown; Fig. 2 is a top plan view of one of the transverse metal frames and cable-winding mechanisms used at the ends of the sectional units; Fig. 3 is a top or plan view of the platform seen in Fig. 1; Fig. 4 is a top plan view of a portion of the transverse frame shown in Fig. 2, the gearing and one cable drum being shown upon a larger scale than in said Fig. 2; Fig. 5 is a sectional view of the same parts, taken in the vertical plane of the axis of the drum-shaft; Fig. 6 is a transverse section through the intermediate or actuating gear of the cable-winding mechanism; Fig. 7 is a view showing the relative arrangement of teeth of the locking or holding ratchet wheel, and of the ratchet hub of the proximate shaft-rotating gear.

The scaffold consists primarily of a floor or platform 1 made up of a series of planks 2 of uniform length and width, advisedly bound at their ends with metal straps or bands 3 to prevent splitting, and to guard against breaking out of the bolts by which the planks are attached to the supporting frames 4. The ends of the planks 2 rest

upon and are secured to the longitudinal side bars of the metallic frames 4, which bars are preferably formed of angle iron members 5 and end members 6, the latter being of iron or steel plate or of suitable castings. These parts are, by preference, securely and permanently riveted together, though bolts or other fastening means may be employed. The members 5 of frames 4 are spaced a suitable distance apart to give adequate room between them for the drums, shaft and gearing, and to permit the planks to extend several inches inward past said members 5, while still leaving between the proximate ends of planks of adjoining sections or units, space for the actuating lever, and for introduction of the hand for manipulation of certain parts when desired. By such provision I am enabled to locate the holes for the attaching bolts sufficiently inward from the ends of the planks to prevent breaking out the wood when the sections of the scaffold are relatively tilted.

7 indicates a shaft journaled at its ends in the end-plates 6 of frames 4, and carrying at opposite ends drums 8 and 9. This shaft is provided with a longitudinally-projecting splines of the drums 8 and 9, or fastening keys of any usual type. Adjacent to or formed upon a head of drum 9 and rotatable therewith, is a ratchet wheel 11 designed to prevent unwinding of the cables 12 from the drums 8 and 9, the teeth of said ratchet being of saw-tooth form and moving beneath the free end of a locking-pawl 13 carried by frame 4. Free rotation of the drums in winding direction is permitted, the beveled or inclined backs of the ratchet teeth riding freely beneath and lifting the pawl 13, which, however, engages with the radial or abrupt faces of said teeth when the drums and ratchet tend to turn in unwinding direction.

To rotate the shaft 7 and turn the drums 8 and 9 in cable-winding direction, there is provided the mechanism shown in Figs. 2 and 3, and on a larger scale in Figs. 4, 5, 6 and 7. This comprises two bevel or miter gears 14 and 15, each provided with a ratchet hub 16, the teeth of which are reversed with reference to those of ratchet wheel 11, and an intermediate gear 17 which meshes at all times with both gears 14 and 15. The intermediate gear 17 is provided with a series of radial sockets 18, here shown

as formed in a cruciform projection 19 on the inner face of said gear, said sockets serving to receive the end of an actuating lever 20. The gears 14 and 15 are loose on the shaft 7, and may be rotated independently thereof, but may be locked to and caused to turn said shaft through the action of pawls 21 and 22 carried by the shaft, or by a sleeve 23 splined or keyed thereto between gears 14, 15, as seen in Fig. 5. As shown in said Fig. 5, the pawls 21, 22 are each formed with a bent spring leaf or arm, and with a thickened head of form alternately to engage and be lifted by the teeth of ratchet hubs 16 of gears 14 and 15, according to the direction of rotation of said gears. The spring-arm of each pawl is attached to sleeve 23, and the bent form of said arms causes the pawls, when free, to stand out from and clear of the ratchet hubs 16. Normally, the pawls are adjusted to engage the teeth of ratchet hubs 16, such adjustment being effected by nuts or internally threaded bands 24 encircling the correspondingly threaded sleeve 23. By turning said nuts toward the ratchet hubs 16, the bent arms of the pawls are pressed inwardly until the heads or pawls proper enter into engagement with the teeth of the ratchet hubs, the resilience of the spring-arms being sufficient, however, to permit backward rotation of said hubs, the long inclined backs of the ratchet teeth then riding beneath and lifting the pawls, as will be readily understood.

By backing either nut or band 24 the pawl which it controls can be freed, and permitted to move outward by reason of the resilience of its spring-arm, to a point beyond the crests of the ratchet teeth. In this way the gear 14 or 15 with which such pawl contacts will be wholly disengaged from shaft 7, and made free to oscillate thereon when gear 17 is oscillated by the lever 20. If both pawls be thus freed, the shaft 7 will be wholly disconnected from both gears 14, 15, but will still be held by the locking pawl 13, unless that be manually lifted from the teeth of ratchet wheel 11. The intermediate gear 17 is mounted on a stub-axle 25 carried by a yoke or frame 26 secured firmly to the frame 4, and having two parallel horizontal arms 26' between which the gearing and sleeve 23 are confined, as seen in Figs. 4 and 5.

It is desirable at times to free the drums 8 and 9 and permit the scaffold to descend by gravity, but it is of course essential that such descent be under perfect control. To this end the actuating gear 17 is advisably formed with a flat rim or periphery, as shown in Figs. 4 and 5, and encircled by a brake-band 27 one end of which is made fast to frame 4 or other fixed support, while the other end is attached to a controlling

lever 28, here represented as terminating in a treadle or foot-plate 29, though obviously the lever may be operated by hand. By releasing either of the pawls 21 and the pawl 13, shaft 7 and drums 8 and 9 will be made free to rotate, the weight of the scaffold causing it to descend. This it can do only by unwinding the cables wound about said drums and thereby turning the drums and shaft 7, which latter turns the pawl-engaged gear 14 or 15 and through it the brake-controlled gear 17. When the scaffold has descended sufficiently, pawl 13 is thrown into locking relation to ratchet 11, and further descent is prevented. Under this construction and arrangement of parts various manipulations of the gearing and drums are possible: First. Both pawls 21 being adjusted to engage their ratchet hubs 16, oscillation of hand lever 20 and consequently of gear 17 will cause like oscillation of gears 14 and 15, but in relatively opposite directions. As all the ratchet hubs 16 have their teeth set to be engaged when the pawls 21 are moving in a direction to turn the shaft 7 and drums in cable-winding direction, such oscillation of lever 20 will cause rotation of the shaft continuously in one direction, both forward and backward strokes of the lever being effective to elevate the scaffold. Second. By freeing one pawl 21 and leaving the other engaged, only one gear 14 or 15 will give motion to the shaft, hence only alternate strokes of the lever will be effective. Third. By releasing the ratchets 16 and 11, the scaffold may be lowered under control of the brake, acting upon gear 17.

It is obvious that a single unit section of scaffolding may be employed, or a number of units, according to the character and extent of the work to be done. Where several units are employed it will be necessary, if the entire platform is to be raised or lowered at once and maintained in horizontal position while so moved, that the several shafts 7 be turned simultaneously and equally. It will sometimes happen, however, that not enough hands will be available to attend the several levers or brakes, and hence it is desirable that the scaffold be capable of elevation or lowering by a single attendant. This is rendered possible by flexibly connecting the ends of sections or units, which may conveniently be done by using bolts 30 for attaching the planks 2 to the frames 4, of sufficient length to permit a relative rocking or tilting movement of the planks and frames. With such connection it is practicable to lower first one end of a section or unit and then the other, care being taken not to permit too great inclination at any time. By working back and forth from end to end of the entire series of sections, the whole scaffold can be brought up to the desired height and made level.

At the extreme ends of the platform, whether of one or of a plurality of sections or units, the planks 2 will extend entirely across the frame 4, which will thus be caused to afford a broad and level bearing for the planks. One plank will in such case, be made shorter than the rest, in order to give access to the bands or nuts 24, and to permit ready insertion and removal of the actuating lever 20. Each frame 4 is also provided with a stake-pocket 31 at the outer end, or it may be at both ends, to receive stakes or posts 32 upon which to carry a rope or guard 33.

So far as I am aware no one has heretofore constructed a scaffold platform of units or sections flexibly connected and capable of being raised or lowered successively, one end at a time, so that the entire platform may be manipulated by one attendant.

Having thus described my invention what I claim is:—

1. A scaffold comprising a plurality of unit sections, each comprising a series of longitudinal planks; metallic frames extending transversely of the planks at each end of the several sections, those at the meeting ends of sections being common to the two sections; bolts carried by the respective transverse frames, passing through the planks supported thereon, and of a length to produce a flexible connection between proximate platform units or sections; whereby one end of each section may be raised or lowered independently of the other and the several sections be thus raised or lowered successively.

2. A swinging scaffold comprising a platform; transversely extending frames beneath the ends of said platform, each provided with a shaft; drums secured upon said shaft to rotate therewith; a ratchet-wheel rotatable with said shaft; a pawl carried by the frame and adapted to engage with said ratchet and prevent backward rotation of the shaft; two miter gears loosely encircling said shaft; means carried by said shaft for locking either or both of said gears to the shaft or freeing either or both at will; an intermediate miter gear meshing with the first-mentioned gears; a lever for oscillating the intermediate gear and through it the gears meshing therewith; and cables wind-

ing about the drums and serving to suspend the scaffold.

3. A scaffold comprising longitudinal floor planks; transverse metallic frames beneath and supporting the ends of said planks, and containing within themselves cable-winding drums and mechanism for turning said drums in winding direction, said mechanism including an actuating gear provided with sockets to receive an actuating lever, a lever to enter said sockets, and suspending cables winding about said drums; whereby the actuating lever may be normally removed and the upper surface of the platform left entirely free of obstructions.

4. In combination with a platform, transverse supporting frames beneath said platform; and means for raising or lowering the platform at will, carried by the respective frames, each such mechanism comprising a shaft, drums mounted upon and rotatable with said shaft, suspending cables winding about said drums, a ratchet wheel carried by said shaft, a locking pawl engaging with said shaft normally to prevent backward rotation of the shaft and drums, two miter gears loosely encircling the shaft, pawls carried by the shaft and serving to engage said gears as the latter are turned, an intermediate gear constantly meshing with the first-named gears, a lever for oscillating the intermediate gear, a brake-band encircling one of said gears, and a lever for causing said band to bind upon said gear when the locking pawl is disengaged to permit descent of the scaffold.

5. The combination with the rotary drum-shaft, of cable-winding mechanism for scaffolding; gears loosely encircling said shaft and provided with ratchet hubs, an externally threaded sleeve intermediate said gears and carried by said shaft; spring pawls carried by said sleeve and tending normally to spring clear of the ratchet hubs; and nuts or bands encircling the threaded sleeve, and serving when properly adjusted to press and hold the pawls in engaging relation to the ratchet hubs.

In testimony whereof I have signed my name to this specification.

JOHN G. BARTELL.
